Primary Examiner—Raphael Barkai**Attorney, Agent, or Firm**—Knobbe Martens Olson & Bear**[57] CLAIM**

The ornamental design for an eyeglass lens, as shown and described.

DESCRIPTION

FIG. 1 is a front perspective view of the eyeglass lens showing our new design;

FIG. 2 is a rear perspective view of the eyeglass lens;

FIG. 3 is a bottom perspective view of the eyeglass lens;

FIG. 4 is a front elevational view of the eyeglass lens;

FIG. 5 is a rear elevational view of the eyeglass lens; and,

FIG. 6 is a side elevational view of the eyeglass lens, the side opposite being a mirror image.
